UNITED STATES PATENT OFFICE.

HOBART M. MYRACLE, EDWARD G. REIGHNER, AND JOHN F. CAILLOUX, OF TONKAWA, OKLAHOMA, ASSIGNORS TO AMERICAN IRON & MACHINE WORKS INC., OF TONKAWA, OKLAHOMA, A CORPORATION OF OKLAHOMA.

SLIP FOR OVERSHOTS.

Application filed December 9, 1924. Serial No. 754,834.

To all whom it may concern:

Be it known that we, HOBART M. MYRACLE, EDWARD G. REIGHNER, and JOHN F. CAILLOUX, citizens of the United States, residing at Tonkawa, in the county of Kay and State of Oklahoma, have invented certain new and useful Improvements in Slips for Overshots, of which the following is a specification, reference being had to the accompanying drawings.

This invention relates to certain improvements upon the slips shown in the application for patent of JOHN F. CAILLOUX, EDWARD G. REIGHNER and HOBART M. MYRACLE, filed on July 10, 1924, Serial #725,226, on releasing hook overshots, and the invention particularly relates to the construction of the toothed slips which are located within the rotary fishing tool and which are adapted to engage with a broken drill pipe and lift the same when the fishing tool is pulled upward.

In the construction illustrated in the prior application above referred to, there is shown a fishing tool or overshot having a cylindrical body portion having a downwardly tapering seat upon which are disposed two semi-circular slips, the interior of the slips being formed with bat-winged left-handed screw-threads, and above these slips is disposed a rubber ring which constitutes not only a packing ring for the slips but also a resilient means for urging the slips downward against the seat.

The object of the present invention is to improve upon the slips as illustrated by so forming the slips that they have interlocking engagement with each other so as to form a more perfect seal in retaining circulation through the drill pipe which is being lifted, and further to prevent the slips from see-sawing or one rising higher than the other when only one of the slips happens to come in contact with the pipe being fished for, this construction also forming a better seat for the rubber packing ring immediately above it.

Our invention is illustrated in the accompanying drawing, wherein:

Figure 1 is a longitudinal sectional view of an overshot constructed in accordance with the invention disclosed in the prior application above referred to but with my improved slips mounted therein;

Figure 2 is a section on the line 2—2 of 55 Figure 1;

Figure 3 is a section on the line 3—3 of 60 Figure 1;

Figure 4 is a perspective view of one of 65 the slips;

Figure 5 is a perspective view of the complementary slip.

Referring to the drawing, 10 designates the cylindrical body portion of the overshot which is downwardly extended at its lower 65 end eccentrically to the body, as at 11. This body terminates in a lateral grab hook 13. This hook 13 is angularly disposed with reference to the longitudinal axis of the fishing tool. The middle of the body 10 is 70 formed with opposed downwardly tapering seats 14 separated from each other by downwardly inclined keys 15. These keys 15 are rigidly fastened opposite each other but the keys are less in height than the height of 75 the seat 14.

Immediately above this tapered portion 14 the wall is cylindrical so as to receive within it the rubber ring 16, and above this portion within which the rubber ring seats 80 the interior of the body is interiorly screw-threaded, as at 17. So far, except for the detailed construction of the keys, I have described what is illustrated in the prior application.

Disposed against the seats 14 and on each side of the keys 15 are the two slips 18. These slips are semi-circular in cross section, as illustrated in Figure 4, and each slip is, of course, tapered. The interior of each slip 90 is formed with bat-winged left-handed screw-threads 19. Each slip is cut away at one edge from its bottom upward, as at 20, this cut-away portion being defined at its upper end by a transversely extending 95 shoulder 21. The opposite edge of the slip is cut away from the upper end of the slip downward, as at 22, the lower edge of this cut-away portion being defined by a shoulder 23. This cut-away portion 22 has a depth 100 equal to the depth of the portion 24 diametrically opposite.

When the slips are placed together, as shown in Figure 1, and the portion 24 is inserted in the cut-away portion 22, the end wall of the slip below the cut-away portion 22 together with the end wall of the cut-away portion 20 define two openings which

receive the keys 15, as shown in Figure 3. The portions 24, however, overlap the shoulder 23 so that there is an interlocking engagement between the slips, and if one slip 5 rises the other slip rises, and if one slip falls the other slip falls. Thus the slips while they can expand or move outwardly independently of each other are conjoined for simultaneous upward or downward 10 movement. The upper portion of the body is interiorly screw-threaded for the reception of the lower end of the drill pipe 25.

With the construction as heretofore described, the tool is run into the hole until 15 the top of the pipe being fished for is found. The fishing tool is then turned to the right until the hook 12 has engaged the upper end of the broken drill pipe and shifted it to the center of the hole. Then the tool is 20 lowered so that the upper end of the pipe being fished for will enter the bowl or body 10. The slips 18 will rise up in the bowl against the action of the rubber ring 16 when the slips come in contact with the 25 broken pipe, allowing the pipe to pass on upward through the body or bowl. When the fishing tool has telescoped upon the pipe being fished for to a sufficient extent, the tool is pulled upward and the slips will 30 move downward, grasping the broken pipe. The pipe is then drawn out of the hole and released. As the slips have bat-winged left-handed screw-threads and as these slips must rotate with the body of the tool, it is 35 obvious that the slips will unscrew from the drill pipe when the tool is turned to the right.

By making the ring 16 of rubber, the ring 40 serves as a packer to keep the return flow of fluid on the outside of the pipe and after hold has been taken on the broken pipe it facilitates circulation through the broken pipe. Thus the ring serves a two-fold purpose, namely that of packing off the circulation and forcing the circulation to the 45 bottom of the pipe being fished for, and also acting as a spring to keep the slips in their proper place when running the tool into the hole and when taking hold of the 50 broken pipe.

In the construction described in the prior application, one of the difficulties was that

the slips were inclined to raise unequally inasmuch as they were not interdigitated or had interlocking connection with each other. 55 Thus one slip would rise higher than the other when only one came in contact with the pipe being fished for. This is obviated in the present construction, as before stated. Furthermore, inasmuch as both slips rise together, they form a better seat for the rubber packing ring and have better engagement with this rubber packing ring, and as the slips overlap across the top of the ribs or keys 15, it is obvious that a much better 60 seal will be formed to retain circulation.

We claim:—

1. A fishing tool comprising a hollow body, a plurality of slips arranged within the body and adapted for gripping an object to be recovered, each of said slips having an upwardly and outwardly inclined outer face, the hollow body having an inclined seat for said slips to rest upon, vertically extending keys arranged on the seat, 70 each of said slips being cut away on one end from the lower end of the slip upward a distance equal to the height of one of said keys and at its other end being cut away from the top of the slip downward a distance equal to the uncutaway portion of the other end of the slip and adapted to receive the uncutaway portion of the next adjacent slip whereby the slips have interlocking engagement with each other for 75 simultaneous upward or downward movement.

2. A fishing tool comprising a hollow body having a downwardly and centrally inclined seat, a plurality of segmental slips 90 arranged within the body, the slips having upwardly and outwardly inclined outer faces engaging said seat and vertical inner faces, each slip having a peripherally extending portion overlapping an adjacent 95 peripheral portion of the adjacent slip in a horizontal plane whereby to cause said slips to move together vertically.

In testimony whereof we hereunto affix our signatures.

HOBART M. MYRACLE.
EDWARD G. REIGHNER.
JOHN F. CAILLOUX.
